UNITED STATES PATENT OFFICE.

CHARLES VOLNEY KERR, OF WELLSVILLE, NEW YORK.

CENTRIFUGAL PUMP.

1,129,038.

Specification of Letters Patent. Patented Feb. 16, 1915.

Application filed September 27, 1913. Serial No. 792,129.

To all whom it may concern:

Be it known that I, CHARLES V. KERR, a citizen of the United States, residing at Wellsville, in the county of Allegany and State of New York, have invented certain new and useful Improvements in Centrifugal Pumps, of which the following is a specification.

My invention relates to centrifugal pumps in general and has for its salient objects to improve the construction of such pumps as to mode of operation and also as to structural details for the accomplishment of the purposes hereinafter set forth.

My object in developing the present type of centrifugal pump, is to secure such a form that will have good efficiency when running at steam turbine speeds, and delivering a large volume of water at high heads, such as used for power plants, water works, marine pumping, and fire and similar service.

A further object of my invention is to construct and arrange the blades of the duplex impeller in such a manner as to replace the expensive and complicated multi-stage centrifugal pumps now generally used for high pressures with virtually a single stage pump of compact and attractive proportions and of the best running qualities, said arrangement at the same time effecting the highest efficiency attainable in said multi-stage pumps. Furthermore, by using a single-stage impeller of "duplex" construction, instead of several impellers of the multi-stage arrangement, the friction and eddy losses due to changes of direction of the water passing from one stage to next succeeding stage are much reduced, and it has been found that a "duplex" impeller as compared with a single impeller designed for the same total head, is analogous to the compound engine compared with the simple engine, where saving in heat losses more than balance the greater resistance of valves and passages and of radiation.

Another object of my invention is to so construct and arrange the blades of the "duplex" impeller, that the blades of the first stage or inlet are preferably of a spiroidal type in order to pick up the fluid and act upon it not too abruptly, so as to turn the same from the axial movement to that of a radial direction to be directly taken up by the centrifugal blades of the second stage and forced out at the discharge.

It is for the purpose of securing to the fullest extent possible the accomplishment of the various objects and desiderata above set forth, that I have devised the present improvements, a preferred form of which is shown in the accompanying two sheets forming part of this specification in which similar reference characters indicate the same parts throughout the several figures of the drawings.

The invention consists of structural characteristics and relative arrangements of elements, which will be hereinafter more fully and clearly described, and particularly pointed out in the appended claims.

In the drawings: Figure 1 is a transverse section of the pump on line I—I of Fig. 2; Fig. 2 is a section on line II—II of Fig. 1; Fig. 3 is an enlarged and fragmentary sectional view of the stepped packing between the casing and impeller; Fig. 4 is a side and enlarged view of the impeller comprising the blades of the first stage or inlet of the water; Fig. 5 is a section of the impeller on line V—V of Fig. 4, one half being in section and the other half being in elevation; Fig. 6 is a side and enlarged view of the impeller comprising the blades of the second stage or outlet of the water; and Fig. 7 is a section on line VII—VII of Fig. 6.

Referring to the drawings 1 is a suitable casing divided on the line I—I and provided with a water inlet 2, which is preferably branched or divided into two symmetrical volute suction chambers 3, 3 for reasons to be hereinafter explained. The interior or central section of the casing has formed therein the rounded or annular opening 4, which leads into the passageway or discharge conduit 5, also preferably of volute shape, said conduit 5 communicating with the outlet opening 6 and being of gradually increasing cross sectional area, as shown in Figs. 1 and 2.

7, 7, are divided bearing heads suitably secured or bolted to the divisions of the casing and in such a position as to firmly carry and support the impeller shaft 8. Said bearing heads may be provided with the usual chambers, lubricant reservoirs and oiling rings, common in this class of machines and need not be shown or further described as they form no essential features of the present invention. The impeller shaft 8 passes through the casing 1 and through suitable stuffing boxes 9, 9, provided with the usual

water sealed glands and is rotatably supported in the bearings 7, 7, as shown. Said shaft may be connected to any form of high speed steam turbine or electric motor by means of a flexible coupling, as shown for example in my Patent No. 1,073,690, dated September 23, 1913. Attached by a suitable key or other means, well known in this class of inventions, to said shaft 8 is an impeller 10 or runner 10 preferably made in three sections 10^a, 10^b and 10^c, as shown in detail in Figs. 4, 5, 6 and 7. The sections 10^a and 10^b comprise the right and left hand "spiroidal" sections for the first stage or inlet, 15 while 10^c is the multi-blade centrifugal for the second stage or discharge, and receives the fluid from the first stage to be herein-after described. While I have shown sections 10^a and 10^b as cored, the same may be 20 solid or in one piece, if so desired and said sections 10^a and 10^b, are secured in place by means of sleeves 11, 11, firmly secured to the shaft 8 by engaging left and right hand screw threads 12 on the shaft adjacent to the 25 impeller 10, as shown, whereby said sections 10^a, 10^b are rigidly held together in a fixed relation and prevented from slipping longitudinally on the shaft 8.

The impeller or runner 10 may be made of 30 semi-steel, crucible steel, or non-corroding alloy or bronze, and when the two sections 10^a and 10^b are properly placed together or assembled, a periphery of V-shaped or conoidal section 13 is formed, as shown in Fig. 35, having a certain and predetermined angle with the axis of the impeller. Vanes or blades 14, 14, are placed on the conoidal periphery or section 13, and are so arranged and machined as to form right and left hand 40 spiroidal working surfaces, as shown in Figs. 4 and 5, said surfaces being generated by moving a line making a constant angle with the axis of the impeller, while moving along a helical directrix, which directrix is 45 inclined at a determined angle to a plane normal to the axis of the impeller. The outer edges of the blades or vanes 14, 14, of each section 10^a, 10^b, are supported and held together by a shroud ring 15, which is preferably cast integral with the impeller sections 10^a or 10^b, and are stepped on the outer 50 side, as shown, the outer side of the inner step of each section 10^a or 10^b being provided with a right or left hand threaded portion 55 16 for purposes to be hereinafter described.

17, are the inlet edges of the blades or vanes 14, 14, which are spiral instead of radial, and 18, 18, indicate the discharge edges of the first stage, said inlet edges or 60 faces 17, 17, being so arranged as to form an angle with the normal outside face or plane of the impeller.

In the form of impeller sections 10^a and 10^b, illustrated in Figs. 4 and 5, six blades 65 or vanes 14 are used on each side, which

number may be varied to suit conditions and capacity, if so desired, and will be fully within the scope of my invention. I have found that this form of impeller or runner sections 10^a and 10^b is not only theoretically correct but it also permits the vanes and spiroidal working surfaces 14, 14, to be readily machined or smoothed, thereby reducing the frictional resistances and insuring uniform and efficient action. Furthermore, by providing two sections 10^a and 10^b instead of a single casting, the same can be cheaply manufactured, easily handled and adjusted and made perfectly rigid and balanced, by being engaged and held together by the multi-blade centrifugal section 10^c, as will be hereinafter described, so that said sections 10^a and 10^b retain their correct form and relationship under the unusual high speeds. While my preferred form is shown in Figs. 4 and 5 in which the blades or vanes 14, 14, on each side are directly opposite each other, I have found that this particular arrangement is not necessary for the successful operation of the pump, and said blades 14 may be staggered by simply turning on the shaft 8, one of the sections 10^a or 10^b of the impeller, through any angle, but preferably one corresponding to one half the peripheral distance between the apexes of the blades or vanes 14.

Surrounding the sections 10^a and 10^b is a multi-blade centrifugal section 10^c which is preferably of one piece and of the form shown in Figs. 6 and 7, provided with a series of blades 19, 19, independent of the number of blades in sections 10^a or 10^b, arranged within the annular and outwardly converging nozzle 20, and having a series of peripheral openings 21. The blades in this centrifugal section have also spiroidal working surfaces generated by a line remaining parallel to the shaft while moving outwardly along a spiral directrix. Said section 10^c is provided on its inner side with right and left hand screw threads 22 which are adapted to be engaged by the corresponding threads 16 on the sections 10^a and 10^b and firmly hold said sections together into a unitary structure, and at the same time said threads prevent them from separating, as during the operation of the pump the turning effort of the impeller tightens the parts together. The section 10^c is so constructed and arranged that when the same is secured to the sections 10^a and 10^b, the inner surface or passageway of the nozzle 20, forms a continuation of the passageways within the sections 10^a and 10^b, and the annular nozzle projects through the annular opening 4 into the volute discharge conduit 5 as shown in Fig. 1.

The walls of the casing 1 at each side of the opening 4 are provided with a ring 23 having a stepped inner periphery corre-

sponding to the stepped periphery of the outer ends of the impeller 10, whereby is formed a fluid packing between the impeller sections 10^a, 10^b and 10^c, and the casing 1.

- 5 During the operation of the impeller 10, rotating rapidly in the direction of the arrows shown in Figs. 1 and 2, the water flows through the intake or inlet 2 and is divided and carried into two volute suction chambers 3, 3, and is then properly taken up in its first stage by the spiral shaped inlet edges 17, 17, on opposite sides of the impeller sections 10^a and 10^b, which enter into the streams of water like a wedge splitting 15 wood, and the spiroidal shaped working faces of the blades or vanes 14, 14, then act flatwise upon the water, instead of edge-wise, as in the usual form of helical pumps, and the water is spirally discharged through 20 a well rounded rotary and annular orifice without any change of direction or appreciable frictional losses, directly into the inlet of the second stage or multi-blade centrifugal 10^c having the same rotary velocity, where 25 it is taken up by the blades 19, 19, within the rotary nozzle 20, and through out spirally into the volute discharge conduit 5, and forced out through the outlet 6. Owing to the stepped joints between the impeller 30 10 and the casing 1 as heretofore explained, the leakage between the discharge and the suction chambers is prevented by the step up fluid packing between said impeller and casing, which packing at the same time prevents any quick endwise movement of the 35 shaft.

While I have shown a double suction pump, it will be readily seen that the same form of impeller and casing having suction and discharge chambers could be adopted for single suction pumps without avoiding the essential features of the present invention of "duplex" form of impeller. It will also be seen that by dividing the casing 1, and bearings 7, 7, as shown in Figs. 1 and 2, one side of the casing can be removed and permit of taking out the impeller and shaft without disturbing the water inlet and outlet connections with the 50 casing 1.

Diffusion vanes could be used in conjunction with the impeller, but I have found them not essential for the efficient operation of the pump and the centrifugal blade could 55 also be used for the first stage or inlet, but I have found that the spiroidal type, as herein shown and described, is far superior in operation and is the preferred type for the reason that it is better adapted to pick up the water and act upon it in making the turn from the axial to the radial, while the centrifugal type is ideal for second stage or discharge.

It will be readily seen that owing to the 60 relation of the volute suction chamber or

chambers 3, the annular opening 4, volute discharge 5, and the sections 10^a, 10^b and 10^c of the impeller 10, the fluid is directed into and moves with the "duplex" impeller in a perfect spiral path, thereby taking up 70 the rapid movement of the impeller without any churning action and producing a smooth and efficient operation of the same.

From the foregoing disclosure, it will be readily seen that the casing, bearings, shaft and impeller and its parts are easily accessible and the construction of the pump is such that all the parts of the same may be cheaply and accurately manufactured, quickly installed and adjusted, or replaced; 75 so as to insure steady and continuous operation under the highest of speeds and with excellent efficiency.

I do not herein claim the construction and arrangement of vanes or blades of the first 80 stage of the impeller *per se*, as shown in Figs. 4 and 5, as that is the subject-matter of a separate and co-pending application filed by me on August 27, 1913, Serial No. 786,946.

What I claim is:—

1. A rotary impeller for centrifugal pumps having a conoidal ridge on which is a series of vanes arranged as spiroidal surfaces, and a hollow annular centrifugal nozzle rigidly connected with the vanes and adapted to receive the fluid directly from the vanes and convey the same through the nozzle. 90

2. A rotary impeller for centrifugal pumps having a conoidal ridge on which is a series of vanes arranged as right and left hand spiroidal surfaces having a spiroidal entering edge, and a hollow annular centrifugal nozzle rigidly connected with the 100 vanes and adapted to receive the fluid directly from the vanes and convey the same 105 through the nozzle.

3. A rotary impeller for centrifugal pumps having an imperforate conoidal ridge on which is a series of vanes arranged 110 as spiroids and a hollow annular centrifugal nozzle rigidly connected with the periphery of the vanes and arranged normal to the axis of the impeller, and adapted to directly receive the fluid from the vanes and convey 115 the same through the nozzle.

4. A rotary impeller for centrifugal pumps having an imperforate conoidal ridge on which is a series of vanes arranged 120 as right and left hand spiroids, and a hollow annular centrifugal nozzle rigidly connected with the periphery of the vanes and arranged normal to the axis of the impeller, and adapted to directly receive the fluid 125 from the vanes and convey the same through the nozzle.

5. A rotary impeller for centrifugal pumps having an imperforate conoidal ridge on which is a series of vanes arranged 130

as right and left hand spirods, shroud rings surrounding and connected with the peripheries of the vanes, and a hollow annular centrifugal nozzle rigidly connected with the shroud rings of the vanes and arranged normal to the axis of the impeller, and adapted to directly receive the fluid from the vanes and convey the same through the nozzle.

6. A rotary impeller for centrifugal pumps comprising a shaft, a conoidal surface surrounding and symmetrically arranged with respect to the axis of said shaft, and having a base which forms a comb or ridge near the periphery of said impeller, a series of vanes or blades arranged as spiroidal surfaces on said conoidal surface, said spiroidal surfaces being generated by a line which moves with a constant angle with respect to the axis of the shaft or impeller while moving along a helical directrix inclined at an angle to a plane normal to the axis of the shaft or impeller, and said conoidal surface being generated by revolving a line about the axis of the shaft, and a hollow annular centrifugal nozzle rigidly connected with the periphery of the vanes and normal to the axis of the shaft, and adapted to directly receive the fluid from the vanes and convey the same through the nozzle.

7. A rotary impeller for centrifugal pumps comprising a rotary shaft, two independent sections surrounding and held against rotation on said shaft and symmetrically arranged with respect to the axis of said shaft and having their bases adjoining each other, a series of vanes or blades arranged as right and left hand spiroidal surfaces on said sections, and a hollow annular centrifugal nozzle surrounding and rigidly connected with said sections and holding the same against separation and longitudinal movement on said shaft, said centrifugal nozzle being arranged normal to the axis of the shaft and adapted to receive directly the fluid from the vanes and convey the same through the nozzle.

8. A rotary impeller for centrifugal pumps comprising a rotary shaft, two independent conoidal surfaces surrounding and held against rotation on said shaft and symmetrically arranged with respect to the axis of said shaft and having their bases adjoining each other which form a central comb or ridge, a series of vanes or blades arranged as right and left hand spiroidal surfaces on said conoidal surfaces, and a hollow annular centrifugal nozzle surrounding and rigidly connected with said conoidal surfaces and holding the same against separation and longitudinal movement on said shaft, said centrifugal nozzle being arranged normal to the axis of the shaft and adapted to receive directly the fluid from the vanes and convey the same through the nozzle.

9. A rotary impeller for centrifugal pumps

comprising a rotary shaft, two independent conoidal surfaces surrounding and held against rotation on said shaft and symmetrically arranged with respect to the axis of said shaft and having their bases adjoining each other which form a central comb or ridge, a series of vanes or blades arranged as spiroidal surfaces on each of said conoidal surfaces, a shroud ring surrounding and connected with the blades for each of the conoidal surfaces and having screw threads on its outer surface, and a hollow annular centrifugal nozzle surrounding and having screw threads on its internal periphery engaging the threads on the shroud rings and holding the said independent conoidal surfaces against separation and longitudinal movement on said shaft, said centrifugal nozzle being arranged normal to the axis of the shaft and adapted to receive directly the fluid from the vanes and convey the same through the nozzle.

10. In a centrifugal pump the combination of a casing having volute suction and discharge conduits and an annular opening connecting the suction with the discharge conduit, an impeller having a central conoidal ridge, spiroidal blades on said conoidal ridge for drawing the water from the suction conduit into and through the impeller, and an annular centrifugal runner surrounding and rigidly connected with the periphery of the impeller and projecting through the annular opening into the discharge conduit, whereby the fluid in the first stage is acted upon by the spiroidal blades of the impeller and conveyed directly and radially into the centrifugal runner to be acted upon in the second stage and forced through the runner and out of the discharge opening.

11. In a centrifugal pump the combination of a casing having volute suction and discharge conduits and an annular opening connecting the suction with the discharge conduit, an impeller having a central conoidal ridge, right and left spiroidal blades on said conoidal ridge for drawing the water from the suction conduit into and through the impeller, and an annular centrifugal runner surrounding and rigidly connected with the periphery of the impeller and projecting through the annular opening into the discharge conduit, whereby the fluid in the first stage is acted upon by the spiroidal blades of the impeller and conveyed directly and radially into the centrifugal runner to be acted upon in the second stage and forced through the runner and out of the discharge opening.

12. In a centrifugal pump the combination of a casing having volute suction and discharge conduits and an annular opening connecting the suction with the discharge conduit, a rotary shaft, an impeller having

a central conoidal ridge on said shaft, right and left spiroidal blades on said conoidal ridge for drawing the water from the suction conduit into and through the impeller, said spiroidal blades being generated by a line which moves with a constant angle with respect to the axis of the shaft or impeller while moving along a helical directrix inclined at an angle to a plane normal to the axis of the shaft or impeller, and said conoidal ridge being generated by revolving a line about the axis of the shaft, and an annular centrifugal runner surrounding and rigidly connected with the periphery of the impeller and projecting through the annular opening into the discharge conduit, whereby the fluid in the first stage is acted upon by the spiroidal blades of the impeller and conveyed directly and radially into the centrifugal runner to be acted upon in the second stage and forced through the runner and out of the discharge opening.

13. A duplex impeller for centrifugal pumps comprising two stages, the first stage 25 consisting of a set of right hand vanes attached to a conoidal body and of a set of left hand vanes attached to a second conoidal

body, and the second stage consisting of a rotary annular nozzle having vanes fixed internally near the periphery thereof, said 30 parts being assembled so that the first stage vanes discharge spirally outward into the second stage vanes.

14. A duplex impeller for centrifugal pumps comprising two stages, the first stage 35 consisting of sets of right and left hand spiroidal vanes arranged to discharge spirally outward and toward each other, and the second stage consisting of an annular rotary nozzle surrounding said spiroidal 40 vanes and having vanes therein adapted to discharge with increased velocity the fluid conveyed thereto by said first stage vanes, said impeller being normally mounted on a rotary shaft and assembled with a casing 45 having volute suction and discharge passages.

In testimony whereof I affix my signature in presence of two witnesses.
